UNITED STATES PATENT OFFICE.

AMBROSE J. QUINLAN, OF AKRON, OHIO.

GAS-BURNER.

No. 839,032.

Specification of Letters Patent.

Patented Dec. 18, 1906.

Application filed November 8, 1905. Serial No. 286,392.

To all whom it may concern:

Be it known that I, AMBROSE J. QUINLAN, a citizen of the United States, residing at Akron, in the county of Summit and State of Ohio, have invented certain new and useful Improvements in Gas-Burners, of which the following is a specification.

My invention relates to improvements in gas-burners, and refers more particularly to a gas-burner adapted to be used for generating heat for brick-kilns, sewer-pipe kilns, sand-driers, furnaces, and for other purposes of the same class.

One object of my invention is the provision of a gas-burner consisting of a series of burners which may be operated as a unit, or the respective burners may be regulated to suit the degree of heat required.

Another object of my invention is the provision of a gas-burner having tubes adapted to extend through the wall of the kiln or furnace, said tubes being made of fireproof material and impervious to the action of the heat.

Other objects of the invention are to provide a device of the character described which will be provided with adjustable means for regulating the supply of air to the mixing-tube and which will consist of but few parts and be simple and practical in every particular.

With these objects in view my invention consists of a gas-burner comprising a gas-chamber having a gas-inlet, a frame secured to the chamber having sleeves formed therein, mixing-tubes slidably secured in said sleeves, ignition-tubes mounted on said mixing-tubes and passing through the wall of the furnace or kiln, said ignition-tubes constructed of fireproof material, and valves in the gas-chamber for regulating the supply of gas to the mixing-tubes.

My invention further consists in certain other novel features of construction and combination and arrangement of parts substantially as disclosed herein.

Figure 1 is a top plan view of my improved gas-burner, showing the wall of the kiln to which it is applied in section. Fig. 2 is a longitudinal sectional view of one of the tubes on line 2 2 of Fig. 1. Fig. 3 is a transverse sectional view on line 3 3 of Fig. 1.

In the drawings, the letter A designates the gas receptacle or chamber, which is provided at one end with the gas-supply pipe B, having the valve C therein, and at the other

end a plug D is provided for use in cleaning the chamber or for any other purpose. A frame E is secured to the chamber by the end brackets F, and the frame extends the entire length of the chamber and has the sleeves G formed therein. The connecting-lugs H are formed between the sleeves, and the frame and chamber are preferably cast or made in one piece, or they may be secured together in any well-known manner. On the side adjacent the sleeves the chamber is formed with a flattened face J, and valve-seats K are formed in this face opposite the sleeves, and valves L are secured in the compartment and adapted to close the valve-seats.

Slidably secured within the sleeves are the mixing-tubes M, and upon the ends of these tubes are the ignition-tubes N. These tubes are of same diameter throughout or are formed with an enlarged portion O, having a seat P therein to receive the mixing-tubes. The ignition-tubes are of fire-clay or some similar fireproof material and are secured in the wall Q of the kiln or furnace. The ends of these ignition-tubes project past the wall of the furnace a short distance so as to properly direct the flame.

The admission of the proper amount of air to the mixing-tubes is obtained by sliding the tubes in the sleeves, and the individual burners may thus be regulated, or the whole may be regulated as a unit by sliding the chamber and frame on the mixing-tubes. The air-supply may be entirely cut off by causing the mixing-tubes to abut against the flat face of the gas-chamber, and it will be evident that the proper mixture may always be obtained.

By making the ignition-tubes of fireproof material a great advantage is derived, as the ends of the tubes will not burn off as they commonly do in the ordinary types of burners, and a great saving will be effected thereby in the cost of repairs, and the burners will be more effective and will last indefinitely.

I have shown my burner as consisting of a series of four burners; but it may be made of any size and number of burners, and by providing the burners with independent valves any one or all of the burners may be used as desired, and the heat may be concentrated in the required spot.

From this description, taken in connection with the drawings, it will be obvious that I have accomplished the objects herein set

forth and have provided a gas-burner which is entirely practical and very desirable.

I claim—

1. A gas-burner consisting of a gas-chamber having a gas-inlet, of a frame secured to said chamber, said frame having sleeves formed therein, said chamber having a flat face adjacent the sleeves, mixing-tubes slidably secured in said sleeves, and fireproof ignition-tubes on said mixing-tubes.
2. A gas-burner consisting of a gas-cham-

ber having a flat face, sleeves secured to the chamber adjacent the said face, mixing-tubes slidably secured in said sleeves, valves for admitting gas to the mixing-tubes, and fireproof ignition-tubes on the mixing-tubes. 15

In testimony whereof I affix my signature in presence of two witnesses.

AMBROSE J. QUINLAN.
